UNITED STATES PATENT OFFICE.

WILLIAM H. LYNCH, OF NEW BEDFORD, MASSACHUSETTS.

AUTOMATIC ICE-ELEVATOR.

No. 875,544.

Specification of Letters Patent.

Patented Dec. 31, 1907.

Application filed July 13, 1907. Serial No. 383,591.

To all whom it may concern:

Be it known that I, WILLIAM H. LYNCH, a citizen of the United States, and a resident of New Bedford, in the county of Bristol and 5 State of Massachusetts, have invented a new and Improved Automatic Ice-Elevator, of which the following is a full, clear, and exact description.

The invention relates to ice harvesting 10 machinery, and its object is to provide a new and improved automatic ice elevator, more especially designed for elevating the cakes of ice from the water-way to the ice house, in a very simple and economical manner and 15 without requiring attention by skilled labor.

The invention consists of novel features and parts and combinations of the same, which will be more fully described hereinafter and then pointed out in the claims.

20 A practical embodiment of the invention is represented in the accompanying drawings forming a part of this specification, in which similar characters of reference indicate corresponding parts in all the views.

25 Figure 1 is a side elevation of the improvement; Fig. 2 is an enlarged side elevation of the lower end of the improvement, parts being in section; Fig. 3 is a plan view of the improvement, showing more particularly the 30 ice carrier in gripping position on the incline, parts being broken out; Fig. 4 is an enlarged plan view of the hoisting drum and connected parts; Fig. 5 is an enlarged side elevation of the switch mechanism for the ice carrier, 35 the switch mechanism being in open position; Fig. 6 is a similar view of the same showing the switch in a closed position on the return or downward travel of the carrier; Fig. 7 is an enlarged transverse section of the 40 improvement on the line 7—7 of Fig. 5, and Fig. 8 is a face view of the planer.

The incline A of the automatic ice elevator connects at its lower end with a frame forming a water box B extending into the water-way 45 C, and the said water box B is open at the front end to permit floating the ice cakes from the water-way into the said water box B, in which one or a number of ice cakes are engaged by an open carrier D for carrying the 50 ice cakes up the incline A to the entrance of one of the chutes E, located one above the other, and leading to the different galleries in the ice house in which the ice cakes are stored.

The carrier D is preferably in the form of a 55 rectangular open frame (see Fig. 3) having side bars D', a front cross bar D² and a rear

cross bar D³, the latter being provided with spikes D⁴ at the inner side for engaging cakes of ice held within the water box B. The forward cross bar D² of the carrier D is connected by ropes or cables F with a hoisting drum G rotating loosely on a continually driven shaft H journaled in suitable bearings at the head of the incline A. On the shaft H is secured a pulley H' connected by a belt H² with a pulley H³ secured on a main shaft H⁴ driven by an engine or other power or mechanism, to continually rotate the shaft H in one direction only.

The hoisting drum G and the shaft H are 70 automatically connected and disconnected by the use of a clutch mechanism I of any approved construction, and having a clutch member I' fixed on one end of the drum G, and a clutch member I² mounted to turn with 75 and to slide on the shaft H, so as to move into and out of engagement with the clutch member I'. The clutch member I² is engaged by a shifting device in the form of a toggle lever I³ controlled by a trip rod J extending down 80 on the outside of the incline A and mounted to slide in suitable bearings A' held on the incline A. On the trip rod J is adjustably secured a lug J' by the use of a set screw J², the said lug J' projecting into the path of one of 85 the trunnions or guide pins D⁵ formed on the ends of the forward cross bar D² of the ice carrier D (see Fig. 3). The rear cross bar D³ is provided at its ends with trunnions D⁶, and the trunnions D⁵ and D⁶ are adapted to travel 90 in main guideways A² formed in the sides of the incline A. The main guideway A² on each side of the incline A connects near its lower end with a branch guideway A³, and the lower ends of the guideways A² and A³ 95 extend or continue in the sides B' of the water box B and lead to approximately horizontally extending guideways A⁴, A⁵ formed in the sides B', and connected at their outer ends with each other by an inclined drop 100 guideway A⁶. The guideway A⁴ has a forward extension A⁷, as plainly shown in Figs. 1 and 2, to form a stop for the trunnions D⁶ at the time the carrier D is in the extreme lowermost position shown in Fig. 2.

A shoe or switch K is arranged at the junction of the guideways A², A³, and the said shoe or switch K is fulcrumed on the side of the incline A and extends upwardly, and is pressed on by a spring K' to normally hold the same in a closed position (see Figs. 2 and 6). Thus when the carrier D travels down-

ward on the incline A, the trunnions D⁶, D⁵ travel over the closed shoe or switch K, and thereby pass from the guideway A² into the branch guideway A³, but when the carrier D 5 travels upward the trunnions D⁵ travel over the closed shoe K up into the guideway A², while the trunnions D⁶ coming up from the guideway A⁴ and lower end of the guideway A² pass under the spring-pressed shoe or 10 switch K, thus lifting the same, to finally pass into the upper portion of the guideway A².

It is understood that when the carrier D travels downward, the trunnions D⁶ pass 15 from the main guideway A² into the branch guideway A³, then into the guideway A⁵, down the incline or drop A⁶ and into the extension A⁷ of the guideway A⁴. When the carrier D travels upward the trunnions D⁶ 20 travel from the extension guideway A⁷ into the guideway A⁴, and then up the guideway A² and under the spring-pressed shoe K, as previously explained.

The guideways A⁴ and their extensions A⁷ 25 are a distance below the level of the waterway C and consequently the rear cross bar D³ is in the rear of the cakes of ice floated into the water box B previous to the carrier D passing into a lowermost position. Now 30 when the carrier D has passed to a lowermost position with the cakes of ice in front of the rear cross bar D³, and the carrier D is pulled upward, then the cakes of ice are carried along by the carrier D and up the incline A, to finally pass onto the corresponding chute E, to then travel by their own weight 35 to the corresponding gallery in the ice house.

The trip rod J is provided near its lower 40 end with teeth or notches J³ adapted to be engaged by a trip lever L fulcrumed at L' on one side of the incline A, and the said trip lever L is provided with an extension arm L² adapted to be engaged by one of the trunnions D⁵, to swing the trip lever L out of 45 engagement with a corresponding notch J³, to unlock the trip rod J, and thereby permit the same to slide down into a lowermost position, to throw the clutch mechanism I into gear, that is, to connect the continually 50 driven shaft H with the drum G at the time the carrier D moves into the extreme lowermost position.

The operation is as follows: When the machine is in use the shaft H is continually running 55 and when the carrier D has passed into a lowermost position, as shown in Fig. 2, and has thus tripped or moved the trip lever L out of engagement with the notches J³, then the clutch mechanism I connects the shaft 60 H with the drum G, to rotate the latter, so that the ropes or cables F are wound upon the drum G, and the carrier D is drawn up on the incline A. The carrier D in its upward movement carries the cakes of ice 65 along, and when the carrier D arrives with

the cakes of ice at the open entrance to a chute E, then the corresponding trunnion D⁵ moves in engagement with the lug J', thus shifting the trip rod J upwardly to actuate the clutch mechanism I, that is, to throw the clutch member I² out of engagement with the clutch member I'. When this takes place the drum G is released and the carrier D by its own weight travels down the incline A back to a normal or starting position, it being understood that during the time the carrier D travels up the incline A, a new load of ice cakes is pushed into the water box B. Now when the carrier D returns and the ice cakes are not pushed far enough into the water box 80 B for the cross bar D³ to clear the ice cakes, then the trip lever L is not actuated, and consequently the trip rod J remains in the locked position with the clutch member I² out of engagement with the clutch member I'. Now when this happens the cakes of ice have to be pushed inward in the water box B sufficiently to clear the rear cross bar D³, so that the carrier D can slide down into its extreme lowermost position for the corresponding trunnion D⁵ to trip the trip lever L, 85 with a view to release the trip rod J. When this takes place, the clutch mechanism I again connects the shaft H with the drum G, so that the latter winds up the ropes or 90 cables F, and the carrier D again starts on its up travel with the cakes of ice.

From the foregoing it will be seen that the shaft H is continually rotated, and consequently needs no attention on the part of the operator, and the carrier D is automatically tripped after it has discharged its load on one of the chutes E, so that no attention whatever is required on the part of the operator except to fill the water box B with cakes 95 of ice for engagement by the carrier D.

By having the extension guideways A⁷ for the trunnions D⁶ to travel in, sufficient room is had for proper resetting of the carrier D, it being, however, expressly understood that 100 the carrier D does not properly reset if obstructed by a cake of ice, as above explained. The sides B' of the water box B may be hinged on the sides of the incline A, if desired so as to permit of swinging the said sides B' upward out of the water, to prevent the sides from freezing in during the night or any other time when the ice elevator is not in use. By adjusting the lug J' on the trip rod J the load of ice cakes carried up by 110 the carrier D can be tripped at any one of the chutes E connected at its entrance end with the incline A in the usual manner.

The drum G may be provided with a manually controlled brake mechanism, in case 115 a friction clutch is used instead of the clutch mechanism I shown and above described.

An ice cake planer N comprising a toothed bar arranged transversely of the chute is secured to the incline A a distance above the 120

shoe or switch K, and this planer N is in the form of a toothed blade extending transversely and secured to the sides of the incline a distance above the slatted bottom thereof, so 5 as to remove any snow or other layers that may be on the top of the cake.

It is understood that when the carrier D pushes the cakes up the incline A they pass the planer N, which by its sharpened edge 10 cuts off any surplus top layers so that the cakes delivered are practically of uniform size. The planer N is arranged at a suitable distance above the carrier, so that the ascending cakes of ice will pass beneath it and 15 by the movement of the cakes, any portion thereof which projects above the planer will be removed.

Having thus described my invention, I claim as new and desire to secure by Letters 20 Patent:

1. An automatic ice elevator comprising an incline, a driven shaft at the head of the incline, a drum mounted to turn loosely on said shaft, a clutch mechanism for connecting and disconnecting the said shaft and the 25 said drum, an open frame ice carrier adapted to travel up and down on the said incline, cables connecting the drum, and means controlled by the movement of the carrier for releasing the clutch mechanism at a predetermined point in the travel of the carrier.

2. An automatic ice elevator comprising an incline, a driven shaft at the head of the incline, a drum mounted to turn loosely on the 35 said shaft, a clutch mechanism for connecting and disconnecting the said shaft and the said drum, an open frame ice carrier adapted to travel up and down on the said incline, a flexible connection between the said ice carrier and the said drum, and a tripping device 40 for the said clutch mechanism and controlled by the said ice carrier, to release the drum at the time the ice carrier reaches a discharging position and to connect the said drum with the driven shaft at the time the ice carrier 45 reaches the extreme lowermost position.

3. An automatic ice elevator comprising an incline, a driven shaft at the head of the incline, a drum mounted to turn loosely on the 50 said shaft, a clutch mechanism for connecting and disconnecting the said shaft and the said drum, an open frame ice carrier adapted to travel up and down on the said incline, a flexible connection between the 55 said ice carrier and the said drum, a trip rod arranged alongside the said incline and connected with the said clutch mechanism, a trip lug adjustably held on the upper portion of the said trip rod, and projecting into the 60 path of the said ice carrier and a trip lever fulcrumed on the incline at or near the lower end thereof and adapted to engage notches on the lower end of the said trip rod, the said trip lever being controlled by the said ice 65 carrier.

4. An ice elevator comprising an incline having main guideways at the sides, each guideway having a return guideway, a water box at the lower end of the said incline and having its sides provided with continuous 70 guideways connected at their forward ends with the said main guideways and the said branch or return guideways, the said continuous guideways having outward extensions, and an ice carrier adapted to travel up 75 and down on the said incline, and having its ends provided with transverse pins adapted to travel in the said guideways of the incline, the rear pins being also adapted to travel in the continuous guideways and the 80 extensions thereof in the water box.

5. An automatic ice elevator comprising an incline, a carrier for carrying the cakes up the incline, and a planer attached to the incline a distance above the bottom thereof to 85 plane the ice cakes carried up the incline by the said carrier.

6. An automatic ice elevator comprising an incline, a carrier for carrying the cakes up the incline, and a planer attached to the incline a distance above the bottom thereof to 90 plane the ice cakes carried up the incline by the said carrier, the said planer being in the form of a blade having a cutting edge.

7. An automatic ice elevator comprising 95 an incline, a carrier for carrying the cakes up the incline, and a planer attached to the incline a distance above the bottom thereof to plane the ice cakes carried up the incline by the said carrier, the said planer being in the 100 form of a blade extending transversely across the incline and secured to the sides of the incline a distance above the bottom thereof.

8. An ice carrier comprising a chute, a water way in which the chute opens, a continuously driven shaft at the top of the chute, a reel on the shaft, a clutch for connecting the reel with the shaft, a rod extending alongside the chute for operating the clutch, means engaging the rod for normally 1 retaining the clutch in inoperative position, ropes winding on the reel, a carrier connected with the free ends of the ropes, said chute being provided with guideways for engagement by the carrier, means in the water way 1 for lifting the lower end of the carrier to pass above the cakes of ice in the water and to drop therebehind when the carrier is in its lowest position, means whereby the carrier may be released, rod engaging means when 1 the carrier is in position behind the cakes, and a stop on the rod for engagement by the carrier to release the clutch.

9. An ice carrier comprising a chute, a water way in which the chute opens, a continuously driven shaft at the top of the chute, a reel on the shaft, a clutch for connecting the reel with the shaft, a rod extending alongside the chute for operating the clutch, means engaging the rod for retaining the clutch in 1.

inoperative position, ropes winding on the reel, a carrier connected with the ropes, means whereby the carrier may release the rod engaging means when it is in its lowest position, and a stop adjustable on the rod for engagement by the carrier to operate the clutch.

10. An ice elevator comprising an incline, a continuously driven shaft at the head of the incline, a drum mounted to turn loosely on the reel, a clutch, mechanism for connecting the drum and the shaft, ropes winding on the drum, an ice carrier connected with the ropes, means for locking the clutch in inoperative position, means whereby the carrier may release the locking means at the commencement of its upward travel, and means operated by the carrier for releasing the clutch at a predetermined point in the travel 20 of said carrier.

11. An ice elevator comprising an incline having main guideways at the sides, each guideway having a return guideway, a water

box at the lower end of said incline and having its sides provided with continuous guideways connected at their forward ends with the said main guideways and the said branch or return guideways, the said continuous guideways having outward extensions, an ice carrier adapted to travel up and down on the said incline and having its ends provided with transverse pins adapted to travel in the said guideways of the incline, the rear pins being also adapted to travel in the continuous guideways and the extensions thereof in the water box, and a spring-pressed shoe in each main guideway at the beginning point of the return guideway.

In testimony whereof I have signed my name to this specification in the presence of 40 two subscribing witnesses.

WILLIAM H. LYNCH.
